UNITED STATES PATENT OFFICE.

MANUEL J. MENDEZ, OF MEXICO, MEXICO, ASSIGNOR TO WILLIAM H. MINER, OF CHAZY, NEW YORK.

TANDEM DRAFT GEAR FOR RAILWAY CARS.

1,427,491.

Specification of Letters Patent. Patented Aug. 29, 1922.

Application filed July 11, 1921. Serial No. 483,666.

To all whom it may concern:

Be it known that I, MANUEL J. MENDEZ, a citizen of Mexico, residing at Mexico city, Mexico, have invented a certain new and 5 useful Improvement in Tandem Draft Gears for Railway Cars, of which the following is a full, clear, concise, and exact description, reference being had to the accompanying drawings, forming a part of this specification.

This invention relates to improvements in tandem draft gears for railway cars.

One object of this invention is to provide an improved tandem draft gear for railway 15 cars which is usable with a single pocket type of yoke and with front and rear sets only of stop or draft lugs.

More specifically, the object of my invention is to provide certain improvements in 20 the type of tandem draft gear shown in O'Connor Patent No. 1,382,221, granted June 21, 1921, and by means of which improvements the parts may be held and shipped in assembled condition; readily inserted in place between the draft lugs of a car underframe; and the over-all length determined and maintained.

Another specific object of the invention is to provide means in a tandem gear of the 30 character indicated so arranged that the shock absorbing devices proper, between the front and rear main followers, may be held centered with respect to the draft sills.

Other objects of the invention will more 35 clearly appear from the description and claims hereinafter following.

In the drawing forming a part of this specification, Figure 1 is a longitudinal horizontal section of a portion of a railway 40 draft rigging showing my improvements in connection therewith. Figure 2 is a vertical transverse section corresponding to the line 2—2 of Figure 1. Figure 3 is a broken side elevational view of the pressure-transmitting means and their relative positions when 45 assembled. And Figure 4 is an end view of one of the intermediate followers employed with my improvements.

In said drawing, the draft sills are indicated at 10—10, the same having secured to 50 the inner sides thereof front stop lugs 11 and rear stop lugs 12, said lugs being spaced apart the present standard distance of 24 $\frac{1}{2}$ ". The rear portion only of a drawbar is indicated at 13, the same having secured

thereto a yoke 14 of the single pocket type. Said yoke and the shock absorbing mechanism therewithin are supported in operative position by means of a detachable saddle plate 25.

The shock absorbing mechanism proper, as shown, comprises front and rear main followers 15 and 16; tandem springs A—A; counterpart pressure-transmitting and spring-retaining casings B—B; intermediate followers C—C; a central column member D; and bolts E—E.

Each of the springs A preferably consists of an outer heavy coil and an inner nested lighter coil, according to well-known 70 practice.

Each casing B is of substantially hollow rectangular form throughout its length and is open at each end. The casings B are preferably made in the form of castings and 75 may be suitably cored on their outer sides, as indicated at 17—17, in order to lessen the weight. At its inner end—that is, the end remote from the corresponding main follower 15 or 16—each casing B is recessed 80 on opposite sides, as indicated at 18—18, for a distance equal to the sum of the thickness of one of the intermediate followers C and the permissible compression stroke of the mechanism. Said recesses 18 are defined on 85 the edges thereof by radially-extending flat faces, as indicated best at 20—20 in Figure 2. Each intermediate follower C is preferably made in the form of a casting and is of generally circular form, as shown at 21

in Figure 4. Formed on diametrically disposed sides of the circular section or disk portion of each follower C are laterally extended flanged sections 22—22. The outer edges of said flanged sections 22, as indicated at 23—23, are adapted to extend substantially flush with the corresponding outer surfaces of the walls of the casings B and the upper and lower edges of the flanged sections 22 are formed on inclines 95 with flat surfaces, as indicated at 24—24, to correspond with the inclined or beveled edges 20 of the casings B so that the intermediate followers are adapted to slide with respect to the casings.

The parts are assembled as best shown in Figure 1 of the drawing—that is, with one casing B and its directly actuated intermediate follower C disposed at an angle of 90° with respect to the other casing B and 110

its corresponding directly actuated intermediate follower C. In this manner, one casing B will directly engage the flanges 22 of one intermediate follower C and the latter will slide within the recesses 18 of the other casing B. As is apparent from an inspection of Figure 1, upon relative approach of the main followers 15 and 16, the intermediate followers C will move correspondingly, thus simultaneously compressing the tandem springs A—A without the use of any tandem yoke or intermediate thimble.

The type of springs used in tandem gears are ordinarily approximately eight inches in outside diameter. Consequently, to avoid any waste of metal the casings B are made as small as possible so as to be able to receive the springs therewith but without allowing the latter any appreciable amount of lateral play within the casings. The ordinary spacing between draft sills is $12\frac{1}{2}$ ", so that, with the type of tandem shock absorbing mechanism shown, there is a difference of approximately $3\frac{1}{2}$ " between the over-all width of the casings B and the distance between the draft sills. In order to prevent the casings and springs, and intermediate followers associated therewith, from shifting out of the center line of the mechanism when ordinary flat followers are employed—such as shown at 15 and 16 of the drawing, I employ the following means.

Each of the main followers 15 and 16 is recessed on its outer side, as indicated at 30, to form a socket for the nut 31 of one of the bolts E, the shank of the bolt passing through a suitable centrally disposed perforation 32 in the main follower. The intermediate followers C are centrally apertured with cylindrical openings, as indicated at 33, so as to allow the column member D to extend therethrough. The column member D is of hollow cylindrical form, closed at its ends, except that the latter are apertured, as indicated at 34, to accommodate the shanks of the bolts E. The heads of the bolts E engage within the column member D against the inner faces of the end walls thereof. To allow for the assembly of the bolts E with the column member D, the latter is formed with an elongated recess 35 on one side thereof through which the bolts E are first inserted and then worked through the end walls of the member D. The diameter of the column member D is made slightly less than the inside diameter of the inner coils of the springs A, so that said springs are centered by said column member, as will be understood. Also, the intermediate followers C will be centered by said column member D.

The over-all length of the column member D is made equal to the difference between

the normal distance between the main followers and the allowable compression stroke of the mechanism, so that, upon full compression of the mechanism, the column member D will have the ends thereof engaged with the main front and rear followers 15 and 16 simultaneously with the engagement of the intermediate followers C with the ends of the recesses 18 of the corresponding opposed casings B. By tightening the nuts 75 on the bolts, it is evident that the over-all normal length of the mechanism may be properly determined and maintained and the springs maintained under an initial compression. The column member D being centered with respect to the main followers 15 and 16, it is obvious that the casings B, intermediate followers C and springs will always be maintained in central position, thus positively preventing the shock absorbing mechanism proper from working to one side nearer one draft sill than the other.

I have herein shown and described what I now consider the preferred manner of carrying out the invention, but the same is merely illustrative and I contemplate all changes and modifications that come within the scope of the claims appended hereto.

I claim:

1. In a tandem shock absorbing mechanism, the combination with front and rear main followers; of two alined and relatively movable casings, each in engagement at its outer end with a main follower; tandem arranged shock absorbing units within said casings; a pair of centrally disposed, detachable, intermediate followers interposed between said shock absorbing units, each of said intermediate followers being engaged by one of the casings and slidable with respect to the other casing, each casing being slotted at its inner end to accommodate one of said followers; and means, adjustable as to length, attached at one end to one main follower and at the other end to the other main follower, said means extending between said main followers, through the centers of the shock absorbing units and through the intermediate followers.

2. In a tandem shock absorbing mechanism, the combination with front and rear main followers; of two alined and relatively movable casings, each casing being in engagement at its outer end with a main follower; tandem arranged shock absorbing units within said casings; a pair of centrally disposed, detachable, intermediate followers interposed between the shock absorbing units, each of said intermediate followers being engaged by one of the casings and slidable within the other casing, each of said intermediate followers being of disk-like form having diametrically disposed flanges; the latter being directly engaged by the corresponding casing, each casing being slotted

at its inner end to accommodate one of said followers; and means, adjustable as to length, attached at one end to one main follower and at the other end to the other main follower, said means extending between said main followers, through the centers of the shock absorbing units and through the intermediate followers.

3. In a tandem draft gear, the combination with front and rear main followers; of alined, partially telescoped casings interposed between said followers; tandem arranged springs, one within each casing, each spring bearing at its outer end upon one of said main followers; a pair of intermediate followers detachable with respect to said casings, each intermediate follower engaging the inner end of one of said springs and adapted to be directly actuated by one of said casings, each intermediate follower being slidable with respect to that casing within which is disposed the spring in contact with said intermediate follower, each casing being slotted at its inner end to accommodate the sliding movement of an intermediate follower; and means for retaining all of said parts in assembled relation and of predetermined over-all length, said means extending between the main followers and attached at its ends thereto, said means extending centrally through the springs and through the intermediate followers.

4. In a tandem shock absorbing mechanism, the combination with front and rear main followers; of two alined and relatively movable casings interposed between said followers; tandem arranged springs within said casings; a pair of centrally disposed detachable intermediate followers interposed between said springs, each intermediate follower being engaged by one of the casings and slidable within the other casing, each casing being slotted at its inner end to accommodate one of said followers; and a centrally disposed column member extending

through said intermediate followers and within the tandem springs, the over-all length of said column member corresponding to the predetermined distance between the main followers at the end of the compression stroke. 50

5. In a railway draft rigging, the combination with draft sills having front and rear stop lugs thereon; of front and rear main followers slidable lengthwise of the sills and adapted to be guided thereby and maintained centrally; alined, partially telescoped casings interposed between said main followers, the over-all width of said casings being appreciably less than the space between the draft sills; tandem arranged springs, one within each casing, each spring bearing at its outer end upon one of said main followers; a pair of intermediate followers detachable with respect to said casings, each of said intermediate followers engaging the inner end of one of said springs and adapted to be directly actuated by one of said casings, each of said intermediate followers being slidable with respect to that casing within which is disposed the spring in contact with said intermediate follower; and means for maintaining said casings, springs and intermediate followers centered with respect to the draft sills, said means including a member extending centrally through the intermediate followers and upon which the latter are slidable, said member extending centrally through the springs, and devices attached to the main front and rear followers 75 for maintaining the central alinement of said member with respect to the main followers. 70

In witness that I claim the foregoing I have hereunto subscribed my name this 28th day of June, 1921. 80

MANUEL J. MENDEZ.
